FLORENCE M. PORTER, OF SEATTLE, WASHINGTON.

CARD INDEX AND REGISTERING MECHANISM.

Application filed February 28, 1923. Serial No. 621,935.

My invention relates to the art of card index and registering mechanism. More particularly my invention relates to a device whereby name strips or cards of members of organizations, conventions, class groups, hotel guests, or documentary designations in office filing devices, may be individually, slidably and removably held in a panel and be clearly visible while so held, together with means for indicating whether the particular individual whose name appears on a given card is present or absent, or such information as may be pertinent to the nature of the use of the device.

The problem of knowing who are present on occasions of large gatherings, or guests in hotels or clubs, is great and the inconvenience on the part of a class leader, chairman or speaker, or other party to know whether to call upon a particular individual is the cause of great inconvenience as well as embarrassment in the loss of time and difficulty in locating the party. The device embodying my invention is designed particularly for the solution of the problem thus presented.

The devices heretofore designed to attain these ends are objectionable in that they are complex and have many parts designed exclusively for the purpose of holding cards with the necessary information. When wires are employed as a part of the holding means they become bent and out of order from use. A primary object of my invention is to provide a card or card strip holding mechanism which is slidably and removably disposed in a panel and is of simple construction.

Again prior art devices in practice are often objectionable in that the maintaining of a given card in a given position is, as a matter of actual practice, often dependent upon the sustaining effect of other cards positioned adjacent thereto. For efficient service the card should be capable of remaining in its position entirely by reason of its own holding mechanism. The dislodgment of the cards from their positions brings the system into great confusion since the cards are usually arranged according to some system, such as an alphabetical or geographical system. It is a primary purpose of my invention to provide a holding means capable of holding a single card member securely against any such unintentional dislodgment.

Further, it is necessary that such cards

in the panel be capable of being displaced when desired to permit of the insertion of a new additional card without disarrangement or removal of the other cards. A primary object of my invention is to provide a holding means that will permit of such intentional displacement of the cards without said disarrangement or removal.

Furthermore, it is often important that a protection be disposed above the cards to protect them from becoming soiled or from unauthorized interference. Such protection may consist of a sheet of transparent celluloid or other transparent medium and this must be removably associated with said card. A primary object of my invention is to provide such a holding mechanism for the cards that will in and of itself be also capable of performing the office of holding and maintaining said protecting transparent medium in position.

It is also necessary that such mechanism be adapted to hold cards of considerable width instead of a mere name strip and it may be necessary that they be disposed one on top of the other. A primary object of my invention is to provide a holding mechanism which will not only be adapted to hold the individual card but also adapted to hold means for holding such groups of cards, and also it is a primary purpose to have this card holding means laterally slidably disposed so that any particular group of cards may be drawn beyond the edge of the panel for such purposes as attracting the attention or for examination by different parties.

One of the conditions which must be met by any device of the character herein involved is that the information must be so held as to be capable of being visualized by those inspecting the device. A further primary object of my invention is to provide a device of the class in question which will positively insure the disclosing of only such information as is required to be disclosed and will positively hold and maintain the card in the desired position so that no partial displacement or sagging is possible to interfere with the neat appearance of the device or the correct display of the desired information. Be it particularly noted that the names or typewritten matter on the cards constitute a large number of lines, as it were, and the slight displacement of such name or typewritten matter is readily noticeable and gives the disagreeable impression inherent

in any type matter which is not disposed in a regular and horizontal arrangement. This is the basis for the condition which makes imperative a holding mechanism which will maintain the cards in position with a very high degree of exactness.

Finally, it is a primary object of my invention to provide such a card index mechanism as will be long-wearing and will be most economical as regards costs of manufacture.

The above mentioned general objects of my invention together with others inherent in the same are attained by the mechanism illustrated in the following drawings, the same being merely preferred exemplary forms of embodiment of my invention throughout which drawings like reference numerals indicate like parts:

20 Figure 1 is a front view in elevation of a panel embodying my invention;

Fig. 2 is a fragmentary view of the reverse side of said panel;

Fig. 3 is a view in cross-section on dotted line 3, 3 of Fig. 1;

Fig. 4 is an enlarged view of the lateral portion of the panel and associated parts;

Fig. 5 is a fragmentary view in perspective of the card holder member;

30 Fig. 6 is a view in elevation of a modified form of said card holder with associated cards;

Fig. 7 is a side view in elevation of a card clip for said modified form of card holder;

35 Fig. 8 is a view in side elevation of still another modified form of a card holder and part of associated name card;

Fig. 9 is a fragmentary view in perspective of the modified form of card holder 40 shown in Fig. 8; and

Fig. 10 is a fragmentary view of a name card used in connection with said card holder shown in Figs. 8 and 9.

Two channel members 11 and 12 are caused 45 to form a panel by being placed back to back in offset relation as shown, said channel members being fixedly held together by spot welding, riveting or otherwise. A hinge member is formed with a tubular part 13 and a projecting part 14 which extends between said channel members and is secured therein so that said channel members may be revolvably mounted on a rod 15 which in turn is held in mountings 16. A wooden strip 17, preferably having beveled sides 18 and 19, is disposed along one lateral edge of each channel member and is preferably releasably held by a angle piece 20 against the said edge portion of the channel. Thus 55 formed the strip may be removably mounted. Said strip is preferably provided with holes 21 to receive marking pegs or pins 22. These marking pins may be of different colored heads to indicate distinctions 60 in the card names opposite which they may

be disposed; or their use may be merely to indicate some information respecting the card opposite which they are disposed.

A card holder 23 is formed preferably of a strip of metal or material of a resilient character. On the end portion three tongue members 24, 25 and 26 are provided. Preferably the lateral tongues 24 and 26 are shorter than the middle tongue 25. Also the middle tongue 25 is caused to be arched 70 in a higher plane than the said lateral tongues so that it is caused to bear against the under side of the channel member at 27. A name card 28 which consists simply of a strip of suitable cardboard without any 80 perforations and preferably of a width equal to that of the card holder is releasably secured in said card holder by pushing one end portion of said name card under the tongues 24 and 26.

85 A sheet 29 of transparent medium, such as transparent celluloid, is preferably provided to lie over said cards and under the end portion of tongue member 25. This sheet is preferably of such width as not to reach to the end of the lateral tongue members, and this sheet is preferably held in said panel with only slight tension from the middle tongue members throughout the length 90 of the panel so that it may readily be pulled out from the panel by simply gripping said sheet at its top.

95 The modified form of the card holder 30 shown in Fig. 6 is preferably provided with tongue members 31, 32 and 33 which may, in this modified form, be of the same length, or the card holder in this instance may be the single tongue member 32, depending upon the use as hereinafter set forth. On the card holder clips 34 are mounted. These 100 clips preferably have a hook part 35 and a foot or guard member 36, said clip having a recess 37 in which the card holder 30 may lie. The clip is preferably freely slidingly 105 mounted upon said card holder. Cards 38, 39 and 40, provided with perforations 41 may be hung upon the hook part 35 of the clip 34.

110 It may be desired to supply the modified form shown in Fig. 6 with a narrow name card such as 28. This may be done by slipping the said card in the recess 37 of the clip 34 between the holding member 30 and the clip. Obviously the foot or guard member 36 will keep said card from dislodgment.

115 The modified form of the card holder 42 shown in Figs. 8 and 9 is intended as individual end card holding means to be 120 releasably secured to the end of a name card 43 provided with perforation 44 in each end portion of said card. A tongue 45 is resiliently arched against the channel member whereby the name card 43 is held in position as respects its end portion. This modi- 125

fied form manifestly reduces the amount of metal employed and results in reducing the cost of the card holding member and greatly reducing the weight of a panel.

5 The mode of operation of the card holding mechanism embodying my invention is as follows:—

On the name card 28 is written the name of the party to be registered together with 10 any data or symbols which may indicate the committee or committees on which the party is serving, or any other desired facts. This card 28 is then placed in the card holder 23 by pushing the ends under the 15 lateral tongues 24 and 26. The holder is then placed in the panel by pushing the end portions under the lateral edges of the channel so that the middle tongue member 25 presses against the under side of the channel at 27. The tongue members 24, 26 and 25, besides functioning as holding means for the card and the holders respectively, also function to keep those holders above from slipping down and over those cards below and render it possible to shove the card holders apart to make space to admit of the 20 insertion of a new card holder with its card. It is plain the lateral tongue members of adjacent holders would strike each other and 25 thus maintain the relative position of the holders. Thus the new card may be inserted in alphabetical or other order without disarranging or removal of the other cards.

30 As the class member, delegate, or other party registered, enters the room, a peg may be inserted by such party in the wooden strip 17 in a hole opposite his name. The class leader with the panel before him may 35 then know who are present in large assemblies and know whom to call upon. In the case of a hotel or club, the clerk will have ready information as to the presence or absence of the party registered. Over the 40 cards so arranged a sheet of transparent medium 29 may be placed by pressing its edges against the cards and slipping the said edges beneath the end portions of the middle tongue members 25, and then pushing 45 the sheet down into the closed end of the panel. When it is desired to remove this covering sheet, the same may be done by lifting it out of the top of the panel, the 50 panel top being preferably left open for this express purpose.

55 Where cards are used as in the case of the modified form illustrated in Fig. 6, the card holding clips 34 are mounted so that they may slide longitudinally of the holder. This 60 provides for the important advantage that the cards relating to any particular name card, (whether same refers to a person or subject matter), may be drawn to one side as shown in dotted outline, Fig. 6. This 65 drawing of the card to one side serves to

mark them for special consideration. For such use it is not intended that the cards be protected by any transparent medium.

Signal tabs consisting of different colors must often be used with cards grouped as 70 here described. Heretofore these have consisted of slips of the nature of riders to be slipped over the top edge of the cards, but these become disengaged in use and result in confusion. Another form of such 75 signals consists of tabs 46 securable to the edge of the card. Manifestly my card-holding mechanism is adapted to use such side signals. These signals function as handles 80 in my invention to lift the card, and thus avoid soiling or wearing the card, so that its legibility is unimpaired. These tabs 46 may be fixedly secured so that they do not become dislodged.

85 The clips 34 also function to keep the holders in place so that they cannot slip past each other. The cards 38, 39 and 40 are provided with perforations 41 so that they may be hung upon the hook part 35. The panel may thus be caused to accommodate several hundred cards if desired. The hook part 35 is provided with a straight end portion 36 so that the cards in front 90 may be lifted to reveal the cards beneath without the raised cards becoming disengaged from the hook 35, as appears from the card in dotted outline position.

95 Having the panels arranged back to back permits of the use of very thin metal and 100 they serve to stiffen and supplement each other. The wooden strip 17 also functions to this same end, thus rendering the panel very light in weight and yet capable of carrying a heavy load of cards. The offset arrangement makes possible the use of the 105 wooden strips 17 on each side, (that is, front and back of the panel), and this results in having the pegs 22 on the left hand side in every case. Having the hinge members 110 extend between the lateral portions of the channel members results in a strong hinge and at a minimum manufacturing cost. Be it particularly noted that the providing of a panel which involves a minimum of manufacturing costs is one of my objects, and 115 it is clear that the metal parts herein described are all designed for ready assembling and may be held together by spot welding.

120 The modified form of card holder shown in Figs. 8 and 9 is designed to hold fast upon the card when the card is removed from the panel and yet be an individual holding means detachably secured to the card.

125 Obviously, changes may be made in the forms, dimensions, and arrangement of the parts of my invention, without departing from the principle thereof, the above setting forth only preferred forms of embodiment. Obviously, the card holder 23 would be op- 130

erative with only two tongue members, but I prefer to have three as above described.

I claim:-

1. A card index mechanism embodying: a panel consisting of two channel members secured together in back to back and off-set relation; a hinge member fixedly secured between said channel members; a wooden strip mounted adjacent one lateral edge of said channel, said strip being provided with holes to releasably receive marking pins; and a card holder releasably held as respects its end portions in said channel members.
2. A card index mechanism embodying: a panel consisting of two channel members secured together in back to back and off-set relation; a hinge member fixedly secured between said channel members; a wooden strip mounted adjacent one lateral edge of said channel, said strip being provided with holes to releasably receive marking pins; a card holder releasably held as respects its end portions in said channel members; and a name card releasably held in said holder.
3. A card index mechanism embodying: a panel consisting of two channel members secured together in back to back and off-set relation; a hinge member fixedly secured between said channel members; a wooden strip mounted adjacent one lateral edge of said channel, said strip being provided with holes to releasably receive marking pins; a card holder releasably held as respects its end portions in said channel members; a name card releasably held in said holder; and a sheet of transparent medium removably disposed over said name card.
4. A card index mechanism embodying: a panel consisting of two channel members secured together in back to back and off-set relation; a hinge member fixedly secured between said channel members; a wooden strip mounted adjacent one lateral edge of said channel, said strip being provided with holes to releasably receive marking pins; and a card holder releasably held as respects its

end portions in said channel members, said end portions having three tongue members folded back over said holder, two of which are shorter than the third, said third tongue member being arched in a higher plane than the said two shorter tongue members, whereby it is caused to bear with a pressure against said channel members.

5. A card index mechanism embodying: a panel consisting of two channel members secured together in back to back and off-set relation; a hinge member fixedly secured between said channel members; a wooden strip mounted adjacent one lateral edge of said channel, said strip being provided with holes to releasably receive marking pins; a card holder releasably held as respects its end portions in said channel members, said end portions having three tongue members folded back over said holder, two of which are shorter than the third, said third tongue member being arched in a higher plane than the said two shorter tongue members, whereby it is caused to bear with a pressure against said channel members; and a name card releasably held in said holder by said lateral tongues, which tongues also function to keep the holders in fixed relation with respect to each other, whereby slipping past one another is avoided.

6. In combination with a card index mechanism embodying: laterally disposed channels, a card holder releasably held as respects its end portions in said channel members, said end portions having tongue members folded back over said holder, one of said tongue members being longer than the other, and being arched in a higher plane than said other tongue member, whereby it is caused to bear resiliently against said channel member.

In witness whereof, I hereunto subscribe my name this 21st day of October, A. D. 1924.

FLORENCE M. PORTER.
